Francis W. Campbell, Liverpool, N.Y., assignor to General Electric Company, a corporation of New York

Filed Jan. 3, 1964, Ser. No. 78,063

Term of patent 14 years

(Cl. D56—4)

FIG.4

FIG. 1 is a front perspective view of a console phonograph or the like embodying my new design, with the phonograph cover in a fully open position;

FIG. 2 is a front perspective view with the phonograph cover in a fully closed position;

FIG. 3 is a front perspective view with the phonograph cover in a partially closed and partially open position;

FIG. 4 is a fragmentary rear elevational view of the console phonograph as shown in FIG. 1, with a portion of the legs and supporting framework being omitted for convenience of illustration; and

FIG. 5 is a right side elevational view of the console phonograph as shown in FIG. 2, the left side elevational view of said phonograph being a mirror image of the right side elevational view.

I claim:

The ornamental design for a console phonograph or the like, substantially as shown and described.
